UNITED STATES PATENT OFFICE.

HENRY BRISTOW, OF BROOKLYN, NEW YORK.

DESIGN FOR A BOOK.

SPECIFICATION forming part of Design No. 26,555, dated January 26, 1897.

Application filed November 25, 1896. Serial No. 613,463. Term of patent 7 years.

To all whom it may concern:

Be it known that I, HENRY BRISTOW, a citizen of the United States, residing in Brooklyn, in the county of Kings and State of New York, have invented and produced a certain new and original Design for a Book, of which the following, with the accompanying drawing, is a specification.

The drawing shows a perspective view of the book in the closed condition.

The leading feature of the design consists of the substantially square covers, with the ornamental leaves, blossoms, and scrolls thereon, and a bow or knot of ribbon on the free edges of the covers.

The invention belongs to that class of covers to hold leaves of cardboard for pressing articles such as doilies.

Within the ornamental design on the cover is a plain space for the reception of any desired inscription.

Referring to the drawing, it will be seen that the cover is embellished by the tastefully-arranged garlands or sprays of leaves and blossoms and graceful scrolls along the four edges of the cover, with a blank space in the center. The ribbons are tied to form a bow or knot at about the middle of the free edges of the covers. The leaves of the book may be of differently-tinted cardboard. 30

I claim—

The design for a book herein shown and described.

In testimony that I claim the invention above set forth I affix my signature in presence of two witnesses. 35

HENRY BRISTOW.
